UNITED STATES PATENT OFFICE

RAYMOND C. HITT, OF SEATTLE, WASHINGTON

AMUSEMENT PIPE

Application filed October 23, 1929 Serial No. 401,690.

This invention relates to novelties and particularly to novelty trick pipes for amusement purposes.

The objects of the invention are to provide 5 an amusement novelty in imitation of a tobacco smoking pipe, with a charge of material in the bowl which will produce a voluminous supply of smoke of any one or more colors, with means for igniting the material when desired, with a cartridge in which 10 the material is carried, adjustably fixed in the bowl of the pipe, but with the hole in the stem not extending to the bowl of the pipe, the device especially designed for outside use, as at fairs, and holiday celebrations.

I have illustrated my invention by the accompanying drawings showing the preferred form, with parts broken away to disclose the interiors, with descriptive numerals there- 20 on.

Numeral 1 represents the bowl of the pipe, in form resembling any tobacco pipe, and preferably made from or resembling a section of a corn cob. The bowl is hollowed out 25 preferably with perpendicular walls 2, and a flat bottom 3, and with a considerable body of solid material at the base 4. The base is provided with a hole 5 in one side, in which is affixed a stem 6, of any shape desired and 30 hole 7 extending only a short distance in the outer end thereof, to convey the illusion of a tobacco pipe.

The bowl is filled with one or more materials for producing a dense smoke of one or 35 more colors, and I have shown in the drawing three different layers of materials placed one above the other, so that they will produce each a different color in sequence. The upper one I have designated as black 8, the next one to represent blue 9 and the lower one to produce yellow 10. These or other colors may be readily produced from chemicals or 40 chemically treated combustible materials, and the colors may be varied to suit the occasions, or will of the users.

As the colors or smokes are usually produced by combustion of the materials in the pipe bowl, I generally provide an ignition 45 fuse 11 in the upper portion of the material, for easy lighting by any match.

The materials for the charges are preferably loaded into tubular cartridges with sides 12 and bottom 13 to fit the inside of the pipe bowl and to be readily inserted therein when smoke is to be produced, or to be removed 55 therefrom for recharging or in exchange for another cartridge for other colors.

The loaded cartridges may be carried by the user separated from the pipe, and the pipe loaned to some uninformed friend for 60 smoking tobacco, and when the friend fails to get the results expected from the pipe, the owner may then insert the cartridge unob- 65 served, and amaze the friend with volumes of colored smoke proceeding from the pipe when lit. Or the pipe may be produced in the presence of observers by the user already charged to light, and when ignited the ob- 70 servers will be surprised and amused to see the smoker using the pipe and producing a 75 cloud of smoke from the bowl, of one or more colors, but without emitting any smoke from his mouth.

In some cases the fuse may be omitted and the upper material may be packed in the pipe 75 direct or in cartridge and so formed or packed that it may be ignited directly from any ordinary match.

Having described my invention, I claim as new for Letters Patent:

An amusement device to be held in the mouth and constructed in the simulation of a tobacco pipe including a hollow bowl, a stem projecting from the bowl and formed at the mouth end with a simulation of the usual 85 smoke duct which terminates short of the bowl, and means carried in the bowl and ar- 90 ranged in layers to produce smoke in different colors when ignited, the relative disposi- tions of the stem and bowl serving to direct the smoke in a direction away from the face of the user.

In testimony whereof I affix my signature.

RAYMOND C. HITT.
